(57) **CLAIM**

The ornamental design for a portion of a display screen with animated graphical user interface, as shown and described.

DESCRIPTION

FIG. 1 is a front view of a first image of a portion of a display screen with animated graphical user interface; and, FIG. 2 is a front view of a second image thereof.

The appearance of a transitional image sequentially transitions between the images shown in FIGS. 1 through 2. The process or period in which one image transitions to another image forms no part of the claimed design.

The broken line showing of the display screen and portions of the graphical user interface forms no part of the claimed design. The transition of elements of the claimed design from a heavier line weight in FIG. 1 to a lighter line weight in FIG. 2 shows a reduction in contrast between these elements and the background of the graphical user interface and forms part of the claimed design.

1 Claim, 2 Drawing Sheets
